UNITED STATES PATENT OFFICE.

HERBERT R. PALMER, OF CLEVELAND, OHIO, ASSIGNOR OF ONE-HALF
TO EDWIN FOWLER, OF CLEVELAND, OHIO.

EXPLOSIVE-ENGINE.

SPECIFICATION forming part of Letters Patent No. 757,632, dated April 19, 1904.

Application filed January 12, 1903. Serial No. 138,595. (No model.)

To all whom it may concern:

Be it known that I, HERBERT R. PALMER, a citizen of the United States, residing at Cleveland, in the county of Cuyahoga and State of Ohio, have invented a certain new and useful Improvement in Explosive-Engines, of which the following is a full, clear, and exact description, reference being had to the accompanying drawing.

10 The object of this invention is to provide an engine wherein the heat of the exploding gases is prevented from directly acting on the lubricating-oil, whereby it is possible to keep the explosive-chamber at a much higher temperature than otherwise, thus saving the heat and doing away with the water-jacket and its attendant disadvantages. I accomplish this by providing on the head of the piston a cup-like extension with its wall close to the wall 15 of the cylinder, but out of contact therewith. The space between the wall of the cup and the wall of the cylinder is so small that the hot gases cannot work down between them to char the oil. At the same time the wall of the cup 20 is kept out of contact with the cylinder, so that no lubricating-oil is required at this point and the lubricating-oil is confined to the surface of the piston proper at a point where it is not heated sufficiently to be 25 charred. I have found by actual test that such a device is eminently practical and satisfactory in operation.

I allow the explosion-chamber of my engine to attain such heat that it itself ignites the 30 charge when it has reached the proper point of compression without a sparking device. The regulation of the compression causing the automatic explosion at just the proper time is accomplished by increasing or decreasing 35 the capacity of the piston-cup. This is also a feature of my invention.

My invention operates very satisfactorily with petroleum, as the internal heat of the explosion-chamber entirely vaporizes petroleum and does not allow it to collect on the 40 walls in the form of soot or smudge, as it would in the usual water-jacketed explosive-engine. As petroleum is not only cheaper than gasolene, but contains more heat units,

the advantages of a petroleum-engine is readily apparent.

The invention consists in the construction and combination of parts hereinafter described, reference being had to the drawing, description, and claims.

The drawing clearly illustrates the invention, being a vertical central section through an upright engine embodying the same and showing the piping for feeding the engine and the sparking-circuit used for starting it.

In the drawing, A represents the frame of a vertical engine. It is formed at its upper end into the cylinder and at its lower end has a crank-chamber in which the crank-shaft B is journaled. The piston is designated C. It 55 has the usual packing-rings c and is connected by the connecting-rod D with the crank. The crank-shaft may have on one end the fly-wheel E and on the other a pinion F, meshing with the gear G of twice the size, which gear 60 carries a pair of cams H H', which operate the valves. Such construction is common in four-cycle engines.

On the upper end of the cylinder proper I provide an extension forming the explosion-chamber A', and on the upper end of the piston proper I likewise provide an extension or cup C'. These extensions are secured to their respective members, preferably with some heat-insulating substance, as mica, between 75 them. These heat-insulators are shown at a' and c', respectively. They are preferred, but are not necessary. In fact, if desired, the extensions A' and C' can be of the same integral castings with the cylinder and piston, re-

80 spectively. The external diameter of the piston-cup C' is slightly smaller than the internal diameter of the cylinder and its extension, so that notwithstanding the expansion due to heat the piston extension does not contact 85 with the cylinder-wall, and therefore no lubricating-oil is necessary for it. The space between the walls is small enough so that the hot gases cannot follow the piston with such rapidity or in such quantity as to heat the 90 lower portion of the piston or the cylinder proper. I have found that a space between the piston-cup and cylinder-wall of one-hun-

dredth of an inch is satisfactory. This reduced diameter extends along the piston for such a distance that the lubricating-oil never reaches a point which is uncovered to the action of the hot gases. The oil is always protected from contact with the hot gases. Now when the explosion takes place between the cylinder-head A² and the piston the latter is driven downward; but the wall of the cup C' 10 protects the cylinder from the heat of the gases. The radiation, without water-jacketing, keeps the cylinder proper at a temperature low enough so that the oil is not charred and keeps the extension A' at a low enough 15 temperature to prevent the premature expulsion of the hydrocarbon, though the temperature of this extension is way above that of the cylinder proper. The explosive mixture enters through the passage a² during the downward 20 stroke of the piston, but is compressed on the upward stroke to a point such that the heat of the extension A' and the cylinder-cup C' automatically explodes the mixture without a sparking device. The amount of 25 this compression is regulated by the addition or removal of plates C², secured within this cup C' to reduce its capacity. The compression is such as to cause the expulsion at just the proper time as the piston is approaching 30 the upper end of the cylinder. Then follows the propulsion-stroke and finally the expulsion-stroke, when the burned gases are forced out through the passage a² into the exhaust-pipe K, the passage being opened at 35 this time by the valve J, which is raised by the exhaust cam-rod J' and the cam H at the beginning of the expulsion-stroke. This movement of the rod J' also operates the small pump L, which forces a charge of petroleum through the pipe N into the bonnet 40 P. This charge is drawn through the pipe N' from a pipe N², through which petroleum is continuously circulated from the tank N³ by a pump Q, continuously operated by the main 45 shaft B. The valves constituting parts of the pumps Q and L are indicated as q and l, respectively, in the piping. As stated, during the expulsion of gases a new charge of liquid petroleum is formed by the pump L 50 into the bonnet P. At the beginning of the return stroke the cam H' acts to raise the rod S', thereby depressing and opening the air-valve S and also the admission-valve S², directly beneath it and impinged by it. These 55 valves are normally seated by their springs. When the cam opens the two of them, the suction caused by the receding piston draws in the air and liquid hydrocarbon, which from the heat of the explosion-chamber is immediately vaporized, the mixture being compressed 60 and exploded on the return stroke.

The operation above described is in the normal running of the engine. For starting the engine I provide a small tank of gasoline 65 and a sparking circuit, which are used in the

usual manner until the engine is under way and the explosion-chamber has become sufficiently heated. During this preliminary operation the petroleum is shut off at the cock N⁴ and it is idly circulated by the pump Q. 70 The gasoline-tank is indicated at T, and it has a pipe T' leading to the bonnet P and has a cock T², which is normally closed. The sparking device, as shown, consists of a pair of electrodes U, circuit-wires U' leading 75 therefrom to the secondary U² of an induction-coil. From the primary U³ of this coil the circuit leads through a battery U⁴ to a pair of contact-strips U⁵, which are closed and released at the proper time, as by a fiber cam H², carried by the gear G. When the engine is under way, the opening of the switch U⁶ in the primary sparking circuit shows whether the explosion-chamber is hot enough to cause the explosions. When it has become 80 hot enough, the cock T² is closed and the cock N⁴ opened and the engine thereafter operated automatically with petroleum. 85

The inside of the explosion-chamber will be very hot; but it is desirable to prevent the 90 conduction of heat to the outer surfaces of the walls thereof. To effect this result, a layer of non-heat-conducting material X is interposed between the inside of said chamber and the outer surface of its walls. In the construction shown this non-conducting material fills a cylindrical recess formed within the walls of said chamber. When so placed, it performs its functions and is entirely out of contact with the contents of said chamber. 95 The space within the upper end of the cup C' is also hot, and in order to prevent as far as possible the conduction of said heat to the wall in the cylinder when the piston has moved down the cylindrical wall of this cup is made 100 hollow and is filled with a non-conducting material X'. In the preferred construction this cup is really made of two cups, the inner one having a flange which is secured upon the end of the outer cup, and the inner cup is of 105 less diameter and length than the outer cup. This leaves a space in the cylindrical walls and in the end of said cup which may be filled 110 with non-conducting material, as stated.

I claim—

1. In an explosive-engine, in combination, a cylinder, a piston therein, a cup with its closed end secured to the explosion end of said piston, said cup being of less diameter than the bore of said cylinder, a lining of heat-insulating material within said cup, and means for protecting said lining. 115
2. In an explosive-engine, in combination, a cylinder, a piston therein, a cup with its closed end secured to the explosion end of said piston, said cup being of less diameter than the bore of said cylinder, a lining of heat-insulating material within said cup, and a metal protector for said lining. 120
3. In an explosive-engine, in combination, 125

5 a cylinder, a piston therein, a cup with its closed end secured to the explosion end of said piston, said cup being of less diameter than the bore of said cylinder, a lining of heat-insulating material within said cup, a protector for said lining, and means for holding said protector within said cup.

10 4. In an explosive-engine, in combination, a cylinder, a piston therein, a cup with its closed end secured to the explosion end of said piston, said cup being of less diameter than the bore of said cylinder, a lining of heat-insulating material within said cup, and a metal cup inside of said lining for protecting the 15 same.

15 5. In an explosive-engine, in combination, a cylinder, a piston therein, a cup with its closed end secured to the explosion end of said piston, said cup being of less diameter than the bore of said cylinder, a lining of heat-insulating material within said cup, and a metal cup inside of said lining for protecting the 20 same, said last-mentioned cup having a flange resting upon the upper edge of said other cup.

25 6. In an explosive-engine, in combination,

a cylinder, a piston therein, a cup with its closed end secured to the explosion end of said piston, said cup being of less diameter than the bore of said cylinder, means within said cup for protecting it from the heat, and an 30 insulating medium between said cup and the explosion end of said piston.

7. In an explosive-engine, in combination, a cylinder, a piston therein, a cup with its closed end secured to the explosion end of said 35 piston, and means for increasing and decreasing the depth of said cup to vary the amount of the compression.

8. In an explosive-engine, in combination, a cylinder, a piston therein, a cup with its closed 40 end secured adjacent to the explosion end of said piston, and plates removably secured within said cup for varying the amount of compression in the cylinder.

In testimony whereof I hereunto affix my 45 signature in the presence of two witnesses.

HERBERT R. PALMER.
